(57) CLAIM

An ornamental design for a footwear article, as shown and described.

DESCRIPTION

FIG. 1 is a front side view of a footwear article according to the present invention.

FIG. 2 is a rear side view of the footwear article of FIG. 1.

FIG. 3 is a right view of the footwear article of FIG. 1.

FIG. 4 is a left view of the footwear article of FIG. 1.

FIG. 5 is a top view of the footwear article of FIG. 1; and, FIG. 6 is a bottom view of the footwear article of FIG. 1. The broken lines in the drawings represent unclaimed subject matter and form no part of the claimed design.

The dash-dot broken line boundaries showing the upper portion of the tongue in FIGS. 1-5 illustrate portions of the footwear article that form no part of the claimed design.

1 Claim, 6 Drawing Sheets
